HENRY VINCENT JAMES, OF RADLETT, ENGLAND

PAPER WEB TENSIONING MEANS FOR REEL-FED PRINTING PRESSES

Application filed July 27, 1931, Serial No. 553,398, and in Great Britain June 26, 1931.

This invention relates to paper reel and web feed control apparatus for rotary printing presses wherein the web is fed to the press continuously from successive reels which are supplied by a magazine reel feed system, anchored belts or bands being applied directly to the periphery of the reel in use for direct reel control and web tensioning purposes.

It is the usual practice to use a number of the said belts, generally four, tied between flexible floor anchorages at their one ends and a rotatable roller at their other ends located in such a position that the belts will be within the arc of the reel throughout its unwinding life, tension being obtained by rotation of the roller actuated by solenoid or torque motor, or by weights suspended directly by the belts, for the purposes of web feed tension and to prevent reel overrun at slow down or stoppage of the press.

My invention consists in improved means for rotating the belt tensioning roller for the purposes described and primarily consists in an epicyclic or three-element gear having one element which I will refer to as the first, mechanically attached to and adapted to rotate the belt tensioning roller, another element, which I will call the second, driven by an electric motor, and the remaining or third element suitably electro-magnetically or electro-dynamically braked for the purpose of varying the effort applied to the first element, means being provided for regulating the brake torque of the third element.

In the method described in the foregoing the electro-dynamic braking device coupled to the third element comprises a direct current generator which is driven continuously through the epicyclic gear by the electric motor coupled to the second element, and means are provided for regulating the speed of the electric motor and/or the speed of the generator, the means for regulating the speed of the generator being in the field and/or armature circuits thereof, for the purpose of controlling the energy generated by the generator and the corresponding energy imparted to the first element for variable web tension and reel rotation control. This arrangement is particularly suited for use when al-

ternating electric current is available for driving the motor coupled to the second element. In this case the motor I employ is most satisfactorily of constant speed type, whilst the direct current generator is usually of self-exciting type. I wish it to be understood, however, that the motor may be of the direct current type; and that the generator may be separately excited where a source of direct electric current is available.

Figure 1 is a side elevation of the means of this invention for rotating the belt tensioning roller.

Figure 2 is a diagrammatic showing of the same.

Figure 3 is an end view showing the drive connected with the belt tensioning roller, the belt being shown in contact with the reel.

In the drawing, the first element of the three-element or epicyclic gear comprises a sprocket wheel 1 rigid with a carrier 2 for two planet wheels 3—3 meshing with the sun wheels 4 and 5 of the second and third elements respectively of the gear. The two latter elements include shafts 6 and 7 on the inner ends of which the wheels 4 and 5 are mounted and the outer ends of which are connected one, as 6, with the rotor 26 of the motor 23 and the other, as 7, with the armature 27 of a direct current generator 24. The sprocket 1 acts through a chain drive 11—12 to turn a belt roller 13 which tensions the belts, such as 14, against the pull of springs 15 anchoring the bottoms of the belts, so that the reel 16 is retarded due to the contact between its periphery and the belt and the running web is tensioned.

The constant speed electric current motor 23 continuously drives a direct current generator 24 through the epicyclic gear described.

The generator 24 is of the shunt wound self exciting type provided with a variable regulator 28 associated with the armature and field circuits and of such an ohmic value that when all resistance in the regulator is introduced into circuit the generator will fail effectively to excite and minimum or negligible torque will be imparted to the first element the generator armature being driven freely in

its bearing by the electric motor 23, the transmission being through gears 4, 3—3 and 5, 3—3 rotating idly on their stubs, which latter remain substantially stationary, the gear case 5 carrier 2 and sprocket 1 being virtually idle and the web tensioning belts (14 Fig. 2) being slack.

As the ohmic value of the resistance in the regulator 28 is decreased the generator will 10 effectively excite and proportionately as the ohmic resistance value in the circuit and corresponding excitation, so will be the energy generated by the generator also the turning effort and torque imparted to the first element, likewise that developed on the sprocket 15 1 through the case 2 and the tension on the reel braking belts for the required web tension and reel rotation control.

Any suitable known torque control means 20 for the generator may be employed, for example the regulator may be coupled potentiometer-wise or the field of the generator may be in long or short connection. The generator may also be of any suitable known 25 kind, and the motor may be speed regulated by any known means whether of the alternating or direct current types.

This application and the claims herein are directed specifically to the form shown, the 30 generic claims covering the invention being contained in my copending application filed August 25, 1930, Serial #477,772.

What I claim is:—

1. In apparatus for the control of a rotary 25 paper reel and the paper web therefrom which supplies a printing machine, a friction band making contact with the periphery of the reel for restraining the rotation of the reel and tensioning the said web, a roller to 30 which one end of the band is attached, an anchorage at the other end of the band and means for rotating the roller for tautening and slackening the belt and so varying the effort of the band on the reel, the means for 35 rotating the roller comprising an epicyclic gear, a coupling between one element of the gear and the roller, a constant speed motor, a coupling between this motor and another element of the gear, a direct electric current generator coupled to a further element of the gear, said generator being driven continuously through the gear by the motor, and a variable ohmic regulator in circuit with the generator for adjustment of the energy generated 40 and the turing effort or torque transmitted, through the gear, from the motor to the element coupled with the roller for imparting a rotary turning effort to the said roller.

2. In apparatus for the control of a rotary 45 paper reel and the paper web therefrom which supplies a printing machine, a friction band making contact with the periphery of the reel for restraining the rotation of the reel and tensioning the said web, a roller to

which one end of the band is attached, an anchorage at the other end of the band and means for rotating the roller for tautening and slackening the belt and so varying the effort of the band on the reel, the means for 70 rotating the roller comprising an epicyclic gear, a coupling between one element of the gear and the roller, an alternating electric current constant speed motor, a coupling between this motor and another element of the gear, a direct current electric generator which is driven continuously through the gear by the said motor, and a variable ohmic regulator in the circuit of the generator for 75 adjustment of the energy generated and the turning effort or torque transmitted, through the gear, to the element coupled to the roller for the purpose of variably imparting a rotary turning effort to the said roller.

3. In apparatus according to claim 2, a regulator introduced into circuit with the 80 electric motor for the purpose of varying the speed of the motor and its turning effort on the generator to impart a rotary turning effort to the element coupled to the roller.

4. In apparatus according to claim 2, regulating means in both the motor and generator circuits for varying the turning effort applied to the roller.

In testimony whereof I affix my signature. 95
HENRY VINCENT JAMES.
